UNITED STATES PATENT OFFICE.

EMIL E. OBERHAUSER, OF DAYTON, OHIO, ASSIGNOR TO THE NATIONAL CASH REGISTER COMPANY, OF DAYTON, OHIO.

CASH REGISTER.

Application filed April 16, 1924. Serial No. 706,892.

To all whom it may concern:

Be it known that I, EMIL E. OBERHAUSER, a citizen of the United States, residing at Dayton, in the county of Montgomery and State of Ohio, have invented certain new and useful Improvements in Cash Registers, of which I declare the following to be a full, clear, and exact description.

This invention relates to improvements in printing mechanism for machines adapted to print on an inserted slip.

The object of this invention is to provide a sales slip supporting means that will permit the severing of a portion of the slip, or not, as desired.

With this and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a perspective view showing a part of the printing mechanism with the invention applied.

Fig. 2 is a portion of the printing mechanism shown partly in section.

Fig. 3 is a detail view of the sales slip feeding mechanism operating cam.

Fig. 4 is a detail sectional view of the upper feed roller.

Fig. 5 is a detail view of the lower feed roller.

Fig. 6 is a detail view of the impression platen operating mechanism.

Fig. 7 is a detail view of the driving means for the sales slip severing knife.

Fig. 8 is a detail view taken on the line 8-8 of Fig. 2 showing the feeding roller adjustment.

In its present form the invention is shown adapted to a cash register of the type shown and described in Letters Patent of the United States, No. 580,378, issued Apr. 13, 1897, to Cleal and Reinhard; and No. 1,539,447, issued May 26, 1925, to Edward J. Von Pein.

The machine to which the present invention is shown applied is of the two motion type, that is, one in which entries are made

by depressing the corresponding keys of the keyboard and then turning the operating handle.

The invention is particularly adaptable to machines used in public utility offices, where statements are rendered to customers, the payment of which by a specified time entitles the customer to a discount.

When payment is made during the discount period, the rendered statement is placed in the machine, the amount of the statement is set up on the keyboard, and, by operation of the machine, is entered into a totalizer and printed in two places upon the statement. A second operation follows, in which the discounted amount, or the amount paid, is registered by entering the amount in a second totalizer, and printing in two places on the statement. In this operation a portion of the statement with one group of printing is severed by a knife mechanism and deposited in a compartment of the machine.

When payment is made after the discount period, the full amount of statement is registered by entering the amount in the first totalizer and printing in two places on the statement. In this operation a portion is severed and deposited in the compartment of the machine.

The detail description of the mechanism shown in the various figures is as follows. The items set up on a keyboard control the positioning of type wheels 30 (Fig. 2) to print corresponding items upon the statement. The type wheels are mounted upon the usual telescopic sleeves, which are supported by a rod 31.

Cooperating with the type wheels, to make a legible impression, is an inking ribbon 32, which is fed from a roller 33 around a guide member 34 over rollers 35 and onto a second roller 36, and reversed by the usual ribbon reversing mechanism, not shown here. The ribbon rolls 33 and 36 are supported by a bracket 37 mounted on two studs on a printer frame 38.

A lug 43 on the printer frame supports any suitable electroplate for printing upon the statement in connection with the type wheels. Cooperating with the type wheels and the electroplate are impression platens 44 and 45 supported in channel bars 46 and

47 mounted upon a horizontal plate 48, which has a downwardly extending arm pivoted at 49 to an arm 50 pinned to a rod 51 supported in the printer frame. A projection extending upwardly from the plate 48 carries a pin 52 which moves between two flanges 53 to guide the plate 48 in its operation.

During the operation of the machine, the rod 51 (Figs. 2 and 6) is rocked twice by the mechanism shown in Fig. 6 to give two operations to the impression platens to print twice upon the statement or slip. Pinned to the rod 51 is an arm 60, which is connected by a link 61 to an arm 62 pivoted on a rod 63 supported in the printer frame. The arm 62 is connected by two adjusting screws 64 to an arm 65, which is also pivoted on the rod 63. Pivoted to the arm 65 is a pitman 66 carrying two rollers 67 and 68, which engage cam plates 69 and 70, respectively. These cam plates are secured to a revolving shaft 76 supported by the printer frame and operated by the driving mechanism of the machine. The cam plates 69 and 70 are so formed that the rod 51 will be rocked to operate the impression platens at the proper time.

As the printing occurs in two different places on the statement or slip, it is necessary to shift the position of the statement after the first printing occurs. To accomplish this, the statement is placed upon a table 77, between a tension roller 78 (Figs. 2 and 4) and a feed roller 79 (Figs. 2 and 5). The tension roller 78 (Fig. 4) is rotatably mounted on a rod 80 supported in a yoke member 81 pivoted on a rod 82 supported in a housing 83, and operates under the tension of a spring 84. The feed roller 79, which cooperates with the tension roller 78, is rotatably mounted upon a stud 85 supported in an arm 86 pinned to a rod 87. The feed roller 79 is raised and lowered into engagement and disengagement with the roller 78 by rocking the rod 87, it being necessary to lower the roller 79 to place the statement in position on the table, and also to remove the statement after the printing operation. Pinned to the rod 87 (Fig. 5) is an arm 88, to which is pivoted a pitman 89 (Figs. 3 and 5) carrying a roller 90 engaging a cam race 91 formed in the side of a disk 92 secured to a driving shaft 93.

To feed the statement or slip between the first and second printing, the roller 79 (Fig. 2) is rotated, first, clockwise and then counter-clockwise, by a pinion 100 secured to the roller and in mesh with a segment arm 101 pivoted on the rod 87. This segment arm has a downwardly extending member 102 (Figs. 2 and 8) having an elongated opening 103, through which an adjusting stud 104 extends to connect the segment arm with a pitman 105. The pitman 105 has an

elongated opening corresponding to the opening 103 in the segment arm for the purpose of moving the stud 104 away from the rod 87 or closer to the rod, as may be desired to change the feed of the roller 79. The forward end of the pitman 105 is guided by a pin 106 engaging a horizontal slot in the pitman. The right hand end of the pitman 105 is bifurcated to engage the rod 63, which acts as a support for this end of the pitman. At each operation of the machine, the pitman 105 is given a reciprocating motion by cam race 107 formed in the forward side of the disk 92, previously described. Engaging the cam race 107 is a roller 108 carried by the pitman 105.

During certain operations of the machine, when it is desired to sever a portion of the statement or slip, and deposit the severed portion in a receptacle located beneath the printing mechanism, the statement passes between a pair of cutting knives, one of which is stationary, and the other one movable. The stationary knife 115 (Fig. 2) is supported by a bracket 116 secured to the printer frame, and held in place by a spring tensioned arm 117. A movable knife 118 is secured to an arm 119 pivoted on the rod 63. This arm carries a roller 120 which engages a cam race 121 formed in the side of a disk 122 rotatably mounted on the shaft 93. The disk 122 is driven by a pin 123 engaging an elongated opening 124 formed in the disk. The pin 123 is mounted in a gear 125 (Fig. 7), which is pinned to the shaft 93, and the purpose of the elongated opening 124 is to permit the disk to receive additional movement to return the movable knife to its home position after the shaft 93 has completed its operation. The power for moving the disk at this time is furnished by a tension spring 126, with one end attached to a link 127, pivoted to a downwardly extending arm 128 of the knife arm 119. With a tension on the arm 119 to move it clockwise, the roller 120, as it engages the incline 129 of the cam race, will move the disk forward until stopped by the pin 123.

It is often desirable, as previously set forth, to print upon the statement or slip without severing it. To permit this, an inclined table 135 (Figs. 1 and 2) is provided, upon which one end of the statement or slip rests during printing and feeding. This supporting member 135 is secured at its upper end to a bracket 136, which is supported by an ear 137 fastened to the printer frame 38 and an arm 138 secured to the bracket 37. The lower end of the supporting member 135 is cut-away to provide a proper clearance for the movable knife 118. With the statement or slip resting upon the table 77, and the supporting member 135, the knife mechanism can operate in the usual way without affecting the statement or slip.

To prevent the slip from coming into contact with the inking ribbon as it is being inserted into the machine with one end resting upon the inclined table 135, there is provided a guard plate 145 (Figs. 1 and 2) which is supported at its left hand end by a stud 146 mounted in the guide member 34. The right hand end of the guard plate is supported by an ear 147 (Fig. 1) fastened with a screw to the printer frame cap 148.

Operation.—The operation of the machine, in connection with the added improvement, is as follows. When the statement or slip is received to be properly received, with the discount to be deducted from the payment of the charge, the slip is placed upon the table 77 with the lower edge in alignment with the line "A", and the upper portion of the statement resting upon the inclined supporting member 135. The amount appearing upon the statement is set upon the keyboard of the machine; the machine operated, and this amount is printed upon the statement in two different places. One impression is made on the portion of the statement which will be known as the voucher, and the other on the main or receipt portion of the statement. After this operation, the statement is moved forward to the line "B" on the table, and the upper end of the slip is placed in the slot 139 (Fig. 1), between the stationary knife and the movable knife, the amount representing the discounted amount, or the amount to be paid, is then set up on the keyboard, and the machine operated as before, with this difference in results, that the voucher portion of the statement will be severed from the receipt portion and deposited in the receptacle 140 beneath the table 77.

When statements are presented for payment, after the discount period, the statements are placed upon the table 77 with the bottom edge in alignment with line "A", and the upper end of the statement in the slot 139. The full amount of the statement is then set up on the keyboard, and the register operated, which prints on the voucher and the receipt end of the statement, and severs the voucher end, as in the operation previously described. It can be seen that the statements or slips can be inserted in the machine, and printed, and a portion severed, or not, as may be desired.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What is claimed is:

1. In a machine of the class described, the combination of means for causing two impressions on a slip of record material, severing means operable at each operation of the machine, means for feeding the slip after the first impression and prior to the second impression, and a slip supporting means adapted to maintain a slip out of cooperative relation with respect to said severing means during feeding operations. 70
2. In a machine of the class described, the combination of means for causing two impressions on a slip of record material, severing means operable at each operation of the machine, a horizontal slip supporting means adapted to support a slip in position to be operated upon by said severing means, and an inclined slip supporting member co-operating with said horizontal supporting means adapted to support a slip in position to render the severing means ineffective. 80
3. In a machine of the class described, the combination of a type wheel, an impression means, a severing means, a supporting table adapted to support a slip of record material, and a guide member adapted to support one end of a slip above said severing means. 85
4. In a machine of the class described, the combination of a type wheel, an impression means, a severing means, a horizontal slip receiving table, and an inclined plate adapted to support one end of a slip to prevent severing thereof by said severing means. 95
5. The combination with a horizontal slip receiving table and a slip severing means; of an inclined guide for holding a slip out of cooperative relation with respect to said severing means. 100
6. In combination with a machine comprising severing means and a table upon which a slip may be placed with one end in cooperative relation with said severing means; of means for supporting said end of said slip out of cooperative relation with said severing means. 110
7. In combination with a printing mechanism comprising a slip receiving table and a severing means so related that a slip may be placed on the table in cooperative relation with said severing means; of means for supporting said slip out of cooperative relation with said severing means. 115
8. In combination with a printing mechanism comprising a slip receiving table and a severing means so related that a slip may be placed on the table to be severed during an operation of the machine; of an inclined support positioned above said severing means to support said slip in operations in which the slip is not to be severed. 120
9. The combination with a printing mechanism comprising a horizontally disposed slip receiving table; of an inclined slip sup- 130

porting plate spaced from said table to permit placing an end of the slip either below said plate or upon said plate.

10. In combination with a printing mechanism comprising a horizontally disposed slip receiving table, and a severing means located at one end of the table in position to cooperate with a slip when placed in

printing position; of a plate positioned above said severing means upon which said 10 end of the slip may be placed to prevent severing of said slip by said severing means.

In testimony whereof I affix my signature.

EMIL E. OBERHAUSER.
